INTERNAL FIRED PERFORATING GUN

James O. Tow, Huntington Park, Calif., assignor
to, McCullough Tool Company, Los Angeles,
Calif., a corporation of Nevada

Application September 20, 1946, Serial No. 698,225

14 Claims. (Cl. 164—0.5)

1

My invention relates in general to guns for firing projectiles, and relates in particular to guns for use in perforating well casing by the firing of a projectile therethrough.

It is an object of the invention to provide a gun having a firing charge of powder disposed behind a projectile and a cooperative arrangement of parts whereby the firing charge is exploded by rearward movement of the projectile by force applied near the rear end of the projectile or at a point spaced from its front end, so that the force employed for the rearward movement of the projectile will be efficiently utilized because of the small loss of pressure out through the front end of the bore of the gun barrel which receives the projectile.

It is a further object of the invention to provide a gun and projectile assembly wherein a spatial enlargement is provided in the gun at a point spaced from the front end of the projectile, and wherein the projectile has a projecting wall extending into this spatial enlargement so as to serve as the rear wall thereof, there being means for applying an ignition effect in this space or chamber formed by the cooperative relation of the projectile and the spatial enlargement. This ignition effect may be produced or exerted by the firing of a small amount of powder in the spatial enlargement or the products of combustion from the firing of a charge of powder in a separate chamber or passage may be conducted into the spatial enlargement so that the force thereof will act against the projecting wall on the projectile and thereby drive the projectile rearwardly so that the firing charge of powder in the firing charge chamber will be exploded and the projectile driven outwardly at high velocity through the gun bore.

It is a further object of the invention to provide a gun and projectile arrangement wherein the projectile has on the rearward portion thereof a ring or flange and means are provided for exerting a force rearwardly against this ring, or against the shoulder provided thereby to drive the ring rearwardly.

A further object of the invention is to provide a gun and projectile arrangement wherein a ring is tightly but removably secured to the rearward portion of the projectile, means are provided for exerting a force against the ring to move the ring and the projectile or the ring alone rearwardly so as to explode the firing charge, the force of which firing charge will drive the projectile forwardly, cause its separation from the ring, and impel it out through the gun bore at high velocity.

2

A further object of the invention is to provide a gun and projectile arrangement wherein a force for application to the projectile rearwardly of its front end is generated by the explosion of a priming charge in a priming charge chamber or passage which communicates with a space adjacent or around the projectile. In the practice of the invention, this priming charge may comprise a charge of powder or a length of explosive priming cord extended along a relatively small passage in the gun body.

It is a further object of the invention to provide a simple gun and projectile assembly of the character hereinbefore described, wherein simplicity and economy of manufacture are attained, this simplified form of the invention having a replaceable gun barrel which fits into a laterally directed opening in the gun body, the body having a passage therein through which the ignition effect or explosion of a priming charge is conducted, and the replaceable barrel having therein passage means communicating with the passage of the gun body for carrying the ignition effect to the side of the projectile and to the ring or other projection thereon, whereby the ring and the projectile or the ring alone will be driven rearwardly to cause explosion of the firing charge in the firing charge chamber lying behind the projectile.

Further objects and advantages of the invention may be brought out in the following specification, wherein I have employed specific and detailed description for the purpose of fully disclosing the invention without placing limitation on the scope thereof set forth in the appended claims.

Referring to the drawings which are for illustrative purposes only:

Fig. 1 is a fragmentary longitudinal section showing a gun body embracing a preferred embodiment of my invention.

Fig. 2 is a cross section taken on a plane indicated by the line 2—2 of Fig. 1.

Fig. 3 is a fragmentary sectional view showing a portion of a gun body and an insertable or replaceable gun barrel therein, embodying my invention.

In Fig. 1 I show a portion of a gun body 11 which, in accordance with accepted gun practice, may comprise a cylindric body of steel. This gun body has, leading in from the side wall thereof, openings 12 to receive projectiles 13. Each opening 12 comprises a bore or cylindric space 14 and a spatial enlargement 15 at the rear end of the bore 14. Rearwardly of the spatial enlargement 15 there is in the body 11

a firing charge chamber 16, the rear wall of which chamber 16 is formed by a plug 17 which is threaded into the body 11 and serves as a removable closure providing access to the firing charge chamber 16 and to the inner end of the opening 12 which comprises the bore 14 and the spatial enlargement 15. In the form of the invention shown, the side wall 18 of the spatial enlargement 15 is continuous with the side wall 19 of the firing charge chamber.

Each projectile 13 has thereon a projection which extends outwardly into the spatial enlargement 15 so as to provide on the rearward portion of the projectile 13 a forwardly facing shoulder or face against which pressure may be applied to move the projectile 13 rearwardly for the purpose of exploding the powder charge 20. In the specific form of the invention shown, the spatial enlargement 15 is cylindrical and is coaxial with the bore 14. The projection on the projectile 13 consists of a ring 21, the outer wall surface of which is contiguous to the wall 18 of the spatial enlargement 15 and the inner surface of which in the preferred practice of the invention grips fairly tightly the rear portion of the cylindric face of the projectile 13. The rear end of the ring 21 has therein an annular channel 22 so as to form a peripheral rearwardly faced lip 23 at the rear end of the ring 21.

In the gun body 11 there is, in duplicate, a priming charge chamber or passage 24 extending longitudinally of the gun body 11 and communicating through ducts 25 with each spatial enlargement 15 ahead of each ring 21. When the gun is loaded for use, the plug 17 is removed, and the projectile 13 with its ring 21 is moved through the firing charge chamber 16 into the position shown, the firing charge 20 is installed and the plug 17 then screwed into place. A seal 26 comprising a plug or disc is then placed so as to close the outer end of the bore 14 and sections of explosive priming cord 27 are placed in the passages 24. The firing of the gun is accomplished by igniting the priming cords 27 by any of the ignition means including caps, fuses, electrical firing devices, etc., now known to the art and therefore not shown in the present application. The combustion products from the explosion of the priming cords 27 is transmitted through the ducts 25 to the forward end of the spatial enlargement 15 and ahead of the ring 21, this explosive force of the combustion products there acting to drive the ring 21 rearwardly. In the preferred practice of the invention, the ring 21 is secured to the projectile 13 in such a manner that the projectile 13 will be carried rearwardly with the ring, thereby suddenly compressing the powder charge 20, thereby causing the firing charge to explode and drive the projectile 13 and the ring 21 forwardly. The ring 21 stops when it reaches the forward end of the spatial enlargement 15 and closes the mouths of the ducts 25. The force of the explosion of the firing charge 20 separates the projectile 13 from the ring 21 and drives the same at high velocity out through the bore 14. A feature of the invention is that, not only are the advantages of driving the projectile 13 rearwardly obtained, but the projectile 13 is given an initial impetus as a result of the restraining action of the ring 21 at the time separation of the projectile 13 and the ring 21 occurs. There are a number of different ways in which the ring 21 can be secured to the projectile 13 so as to accomplish a connection between the ring 21 and the projectile 13 which will carry the projectile 13 rear-

wardly with the ring 21 when the force of the priming charge 27-27 is applied to the front face of the ring 21. For example, there may be a threaded engagement between the ring 21 and the projectile 13 of sufficient strength to attain the desired releasable connection between these parts, or the ring 21 may be pressed, sweated, soldered or brazed on the rear end of the projectile 13.

10 In the form of the invention shown in Fig. 3, I provide a gun body 11' having at least one transverse opening 30 and at least one removable gun barrel 31. The recess 30 and the gun barrel 31 are cylindrical and are of such cooperative size that the gun barrel 31 will fit snugly in the recess 30. The gun barrel 31 includes elements previously described in detail with relation to Figs. 2 and 3, and accordingly these parts will be identified by the same numerals and the detailed description thereof will not be repeated.

The gun body 11' has therein an axial passage 24' which intersects the median portion of the recess 30. An annular channel 32 is formed in the exterior of the gun barrel 31 in a position to communicate with the passage 24', and the gun barrel 31 also has an ignition passage 25' leading inward from the channel 32 to the front end of the spatial enlargement 15. In the operation of this form of the invention, an ignition charge 30 of powder 35 is placed in the forward portion of the spatial enlargement 15 ahead of the ring 21 and means are provided for the firing of this powder charge 35 so that the force of its explosion will drive the ring 21 and the projectile 13 rearward to cause explosion of the firing charge 20 disposed in the firing charge chamber 16 behind the projectile 13 and the ring 21. The specific means which I have provided for the firing of the powder charge 35 includes the duct 25' and the passage 24' whereby an ignition effect may be transmitted to the powder charge 35. For example, a charge of powder may be exploded in the passage 24' or in a chamber, not shown, communicating with this passage 24'. Combustion products therefrom, including pressure and flame, are transmitted through the duct 25' to the powder charge 35, causing the same to explode. The explosion of the powder charge 35 serves as an ignition means for the firing charge 20, since the force of its explosion drives the ring 21 and the projectile 13 rearwardly. It will be understood that in one practice of the invention, the powder charge may be omitted and the explosive force transmitted from the passage 24' through the duct 25' to the spatial enlargement 15 ahead of the ring 21 is utilized to drive the ring 21 and the projectile rearwardly.

I claim as my invention:

1. In a gun and projectile arrangement, the combination of: a body having a projectile receiving bore, a spatial enlargement at the rear end of said bore, a firing charge chamber communicating with the rear end of said bore, and a passage communicating with said spatial enlargement; a projectile in said bore having thereon a projection extending outwardly into said spatial enlargement rearwardly of said communication of said passage with said spatial enlargement, the transverse area of said projection being substantially equal to the transverse area of said spatial enlargement, and said projection being releasable from said projectile as said projectile moves out through said bore; a firing charge in said chamber; and means for applying pressure through said passage into said spatial enlarge-

ment ahead of said projection, to drive the projectile rearwardly whereby said firing charge will be exploded.

2. In a gun and projectile arrangement, the combination of: a body having a projectile receiving bore, a spatial enlargement at the rear end of said bore, a firing charge chamber communicating with the rear end of said bore, and a passage communicating with said spatial enlargement; a projectile in said bore having thereon a projection extending outwardly into said spatial enlargement rearwardly of said communication of said passage with said spatial enlargement, the transverse area of said projection being substantially equal to the transverse area of said spatial enlargement, and said projection being releasable from said projectile; a firing charge in said chamber; an ignition charge of powder; means for firing said ignition charge; and wall means for directing the products of combustion from said ignition charge into said passage.

3. In a gun and projectile arrangement, the combination of: a body having a projectile receiving bore, a spatial enlargement at the rear end of said bore, a firing charge chamber communicating with the rear end of said bore; a projectile in said bore having thereon a projection extending outwardly into said spatial enlargement, the transverse area of said projection being substantially equal to the transverse area of said spatial enlargement, and said projection being releasable from said projectile; a firing charge in said chamber; an ignition charge; means for firing said ignition charge; and wall means for directing the products of combustion from said ignition charge into said spatial enlargement ahead of said projection.

4. In a gun and projectile arrangement, the combination of: a body having a projectile receiving bore, a spatial enlargement at the rear end of said bore, a firing charge chamber communicating with the rear end of said bore; a firing charge in said chamber; a projectile in said bore having thereon a projection extending outwardly into said spatial enlargement, the transverse area of said projection being substantially equal to the transverse area of said spatial enlargement, and said projection being releasable from said projectile as said projectile moves out through said bore; means for accumulating a fluid pressure; and means for directing said fluid pressure into said spatial enlargement ahead of said projection to drive the projectile rearwardly and thereby cause explosion of said firing charge.

5. In a gun and projectile arrangement, the combination of: a body having a projectile receiving bore, an annular spatial enlargement at the rear end of said bore, a firing charge chamber communicating with the rear end of said bore, and a passage communicating with said spatial enlargement; a projectile in said bore having thereon a ring extending outwardly into said spatial enlargement rearwardly of said communication of said passage with said spatial enlargement, said ring having a transverse area substantially equal to the transverse area of said spatial enlargement, and said ring being separable from said projectile as said projectile passes out through said bore; a firing charge in said chamber; and means for applying pressure through said passage into said spatial enlargement ahead of said ring, to drive the projectile rearwardly, whereby said firing charge will be exploded.

6. In a gun and projectile arrangement, the combination of: a body having a projectile re-

ceiving bore, an annular spatial enlargement at the rear end of said bore, a firing charge chamber communicating with the rear end of said bore, and a passage communicating with said spatial enlargement; a projectile in said bore having thereon a ring extending outwardly into said spatial enlargement rearwardly of said communication of said passage with said spatial enlargement, said ring having a transverse area substantially equal to the transverse area of said spatial enlargement, and said ring being separable from said projectile; a firing charge in said chamber; an ignition charge of powder; means for firing said ignition charge; and wall means for directing the products of combustion from said ignition charge into said passage.

7. In a gun and projectile arrangement, the combination of: a body having a projectile receiving bore, an annular spatial enlargement at the rear end of said bore, a firing charge chamber communicating with the rear end of said bore; a projectile in said bore having thereon a ring extending outwardly into said spatial enlargement, said ring having a transverse area substantially equal to the transverse area of said spatial enlargement, and said ring being separable from said projectile; a firing charge in said chamber; an ignition charge; means for firing said ignition charge; and walls defining passage means which direct the products of combustion from said ignition charge into said spatial enlargement ahead of said ring.

8. In a gun and projectile arrangement, the combination of: a body having a projectile receiving bore, an annular spatial enlargement at the rear end of said bore, and a firing charge chamber communicating with the rear end of said bore; a firing charge in said chamber; a projectile in said bore having thereon a ring extending outwardly into said spatial enlargement, said ring having a transverse area substantially equal to the transverse area of said spatial enlargement, and said ring being separable from said projectile; means for accumulating a fluid pressure; and means for directing said fluid pressure into said spatial enlargement ahead of said ring to drive the projectile rearwardly and thereby cause explosion of said firing charge.

9. In a gun and projectile arrangement, the combination of: a body having a bore to receive a projectile and a firing charge chamber communicating with the rear end of said bore; a firing charge in said chamber; a projectile in said bore having at its rear end an annular flange which expands behind the rear end of said bore within said firing charge chamber and substantially touches the side wall of said chamber; and means comprising a source of fluid pressure separate from said firing charge adapted to apply pressure against the front of said flange to move said projectile rearwardly and thereby cause explosion of the firing charge disposed in said firing charge chamber.

10. In a gun and projectile arrangement, the combination of: a body having a bore to receive a projectile and a firing charge chamber communicating with the rear end of said bore; a firing charge in said chamber, a projectile in said bore having at its rear end an annular flange which expands behind the rear end of said bore within said firing charge chamber and substantially touches the side wall of said chamber; an ignition charge of powder; means for firing said ignition charge; and means comprising walls for directing the products of combustion from said

ignition charge against the front face of said flange to drive said projectile rearwardly and thereby accomplish explosion of said firing charge.

11. In a gun and projectile arrangement, the combination of: a body having a projectile receiving bore, a spatial enlargement at the rear end of said bore, a firing charge chamber communicating with the rear end of said bore; a projectile in said bore having thereon a projection extending outwardly into said spatial enlargement, the transverse area of said projection being substantially equal to the transverse area of said spatial enlargement, and said projection being releasable from said projectile; a firing charge in said chamber; and ignition producing means acting in said spatial enlargement ahead of the rear end of said projection.

12. In a gun and projectile arrangement, the combination of: a body having a projectile receiving bore, a spatial enlargement at the rear end of said bore, a firing charge chamber communicating with the rear end of said bore; a projectile in said bore having thereon a projection extending outwardly into said spatial enlargement, the transverse area of said projection being substantially equal to the transverse area of said spatial enlargement, and said projection being releasable from said projectile; a firing charge in said chamber; an explosive in said spatial enlargement ahead of said projection and means to ignite said explosive.

13. In a gun and projectile arrangement, the combination of: a body having a projectile receiving bore, a spatial enlargement at the rear end of said bore, a firing charge chamber communicating with the rear end of said bore; a firing charge in said chamber, a projectile in

5 said bore having thereon a projection extending outwardly into said spatial enlargement, the transverse area of said projection being substantially equal to the transverse area of said spatial enlargement, and said projection being releasable from said projectile; an ignition charge; and walls forming an ignition passage connecting said ignition charge and said spatial enlargement ahead of the rear end of said projection.

10 14. In a gun and projectile arrangement, the combination of: a body having a projectile receiving bore, an annular spatial enlargement at the rear end of said bore and a firing charge chamber at the rear end of said bore; a firing charge in said chamber; a projectile in said bore; a member at the rear end of said projectile providing an annular wall which projects radially in said spatial enlargement, said member having a transverse area substantially the same as the transverse area of said spatial enlargement; and walls forming a passage communicating with said spatial enlargement ahead of said annular wall for transmission of pressure to the front face of said member.

25 JAMES O. TOW.
